[57] CLAIM

The ornamental design for a carpet sweeper, as shown and described.

DESCRIPTION

FIG. 1 is a perspective view of a carpet sweeper which embodies our design, the broken lines being for environmental purposes only and form no part of the claimed design;

FIG. 2 is a side elevational view thereof, the opposite side being a mirror image thereof;

FIG. 3 is a top plan view thereof;

FIG. 4 is a front elevational view thereof;

FIG. 5 is a bottom plan view thereof;

FIG. 6 is a rear elevational view thereof;

FIG. 7 is a perspective view of a carpet sweeper housing which embodies a modified form of our design, the broken lines being for environmental purposes only and form no part of the claimed design;

FIG. 8 is a side elevational view thereof, the opposite side being a mirror image thereof;

FIG. 9 is a top plan view thereof;

FIG. 10 is a front elevational view thereof; and,

FIG. 11 is a rear elevational view thereof.
